UNITED STATES PATENT OFFICE.

CARL C. RIOTTE, OF NEW YORK, N. Y., ASSIGNOR TO CARLTON R. RADCLIFFE, OF SAME PLACE.

DESIGN FOR AN ENGINE-FRAME.

SPECIFICATION forming part of Design No. 31,805, dated November 7, 1899.

Application filed May 9, 1899. Serial No. 716,173. Term of patent 7 years.

To all whom it may concern:

Be it known that I, CARL C. RIOTTE, a citizen of the United States, residing in the borough of Manhattan, city, county, and State 5 of New York, have invented or produced a certain new and original Design for Engine-Frames, of which the following is a specification.

This design relates to engines, and particularly to marine engines, and aims to provide an original shape for the frames, shells, or bodies thereof.

The new design is illustrated in the accompanying drawings, in which—

15 Figure 1 is an end elevation of an engine-frame embodying the new design. Fig. 2 is a side elevation thereof. Fig. 3 is a top view thereof, and Fig. 4 is a fragmentary elevation of the reverse side of the body or capital.

20 Referring to the drawings, A represents the end of the base, B the end of the pedestal, C the columns, and D the end of the body or capital, of the engine-frame embodying the new design, and A' represents the side of the base, B' the side of the pedestal, and D' the side of the capital thereof; A'', a lateral projection on the base; E, a cylindrical enlargement therefor; F, a cylindrical protuberance therefrom; G, a lateral member, and H the 25 top of the capital.

According to the features of the new design the end of the base A is substantially semicircular, and its side is substantially semi-cylindrical, and it has the lateral projection 30 A'', which is semicylindrical and of smaller diameter than the part A'. The base has a flat top or band a above the center of the circle from which its side walls are struck, and the lateral extension has a similar band a' coincident with its center. A cylindrical projection b is disposed at one end of the base, which projection is surrounded by two rectangular square members or bands c c'. At 35 the outer end of the extension A'' there is the cylindrical protuberance F, which has a plurality of ring-like members a'' on its lower side. The band a is of relatively great projection at both sides of the base and of relatively slight projection at its end. Beneath 40 the band a the side A' has two parallel oblong projecting portions b' and three diagonal bands or uprights b''.

The end of the pedestal B is vertical, hav-

ing parallel top and bottom walls and inclined side edges. The sides B' of the pedestal are 55 straight inclined walls having each a central panel c'', surrounded by a rectangular border d. At its bottom the pedestal has a border d'.

Two columns C are disposed above the pedestal and between it and the body or capital. 60 Each column is cylindrical, and they are spaced apart. A border d'' connects the columns at bottom. The columns unite with the border and with the capital with slight curves. A third and smaller cylinder I is disposed between the columns, is parallel therewith, and extends from the border d'' to the capital. 65

The end D of the capital is cylindrical, and its obverse side D' is parallel, smooth, and oblong in side elevation. Two ring-like bands 70 f are disposed on the end D, and two depending portions f' are disposed on the side D'. The reverse side wall D'' of the body or capital is oblong, smooth, and flat and has at its top two elongated depending protuberances 75 h, each having two circular recesses h' in its face, and at bottom it has an irregularly-formed protuberance i, having a large circular figure i' and a small circular figure i'' disposed upon it. 80

The top wall H is flat and of general oblong shape, having parallel side walls and semi-circular ends.

The protuberance G projects from the side wall D'' in a curve f'', extends vertically downward in a cylindrical portion g parallel with the column C, and then diagonally downward in a cylindrical portion g' parallel with one side wall B' of the pedestal. The protuberance has a band g'' at its lower end. 85 90

Above the lateral extension A'' is the cylinder E, which has abrupt ends j j' and an intermediate cylindrical band j'', having a cross-band k, spaced apart from a parallel cross-band k'.

What I claim is—

The design for an engine-frame, substantially as shown and described.

In witness whereof I have hereunto signed my name in the presence of two subscribing 100 witnesses.

CARL C. RIOTTE.

Witnesses:

GEORGE H. FRASER,
CARLTON R. RADCLIFFE.
